A winding mechanism for watches particularly back winding watches in which a winding stem has a winding gear rotational thereon provided with ratchet teeth. The winding gear meshes with a ratchet gear at all times. A clutch gear is mounted for rotation with the winding stem and is axially slidable thereon. It is biased by a spring toward engagement with the ratchet teeth of the winding gear by means of a spring. The clutch gear is declutched when the winding stem is pulled out for a hand-setting operation. The clutch gear is engaged by an enlarged diameter portion of the winding stem lifting it so that it disengages from the ratchet teeth of the winding gear against the action of its biasing spring.

5 Claims, 2 Drawing Figures

FIG. 1

FIG. 2

WINDING MECHANISM FOR BACK WINDING WATCH

BACKGROUND OF THE INVENTION

This invention relates generally to a winding mechanism for a watch and more particularly to back winding watches and winding mechanisms therefore.

In conventional watches a winding gear is mounted on the winding stem and is engaged with a ratchet gear in a winding position of the winding crown and stem. The winding gear is disengaged from the ratchet gear when the winding crown and stem are pulled axially to a hand-setting position. Generally, in returning the winding stem from its hand-setting position to its winding position trouble is encountered in coupling or engaging the winding gear with the ratchet gear teeth.

Another problem encountered in this kind of situation in conventional watches is that the winding crown cannot be rotated in a reverse direction when it is in its winding position.

SUMMARY OF THE INVENTION

It is an object of the present invention to provide a winding mechanism for watches and more particularly back winding watches, wherein the winding gear is continuously meshing with a ratchet gear thereby insuring continuous readiness for winding a watch.

Another object of the present invention is to provide the winding mechanism for a thin-type back winding watch having a winding crown which may be reversely rotated and generates a sound signal to prevent damage of the gears.

The watch winding mechanism in accordance with the invention has a winding stem mounted for rotation and movable axially from a winding first position to a hand-setting second position. A clutch gear is mounted coaxially with the winding gear and is axially slidable on the winding stem for rotation therewith. Spring means constantly, resiliently biases the clutch gear axially of the winding stem in a direction for meshing with the driving gear clutch teeth. The spring means allows the clutch gear to be displaced axially away from the clutch if the clutch gear is rotated by the winding stem in a direction opposite to the winding direction for winding the winding mechanism. Means are provided on the winding stem to displace the clutch gear axially away from the winding gear against the biasing force of the spring means, when the winding stem is moved axially to its second position.

BRIEF DESCRIPTION OF THE DRAWINGS

Other objects and advantages of the winding mechanism in accordance with the invention will appear from the following description of an example of the invention and the novel features will be particularly pointed out in the appended claims and drawings in which:

FIG. 1 is a fragmentary elevation view, partly in section, of a watch with a watch winding mechanism according to the invention; and

FIG. 2 is a fragmentary elevation view, partly in section, of a second watch embodiment with a second embodiment of a winding mechanism in accordance with the invention.

DESCRIPTION OF THE PREFERRED EMBODIMENTS

The present invention will be fully described by way

of two embodiments embodying the invention and in connection with accompanying drawings. In FIG. 1 a winding stem 1 is rotationally and axially slidable in a watch structure. The winding stem 1 is provided with a winding crown 2 secured to the winding stem 1 in a conventional manner and having a cylindrical portion 2a. The winding stem extends axially through openings in a casing member 3, a barrel bridge 4 and a plate 5. A round portion 1a thereof is rotatable in the barrel bridge 5.

The watch is provided with a hand-setting mechanism for setting the hands, not shown, of the watch comprising a hand-setting or intermediate gear 6 meshing with a gear train including a minute gear for setting the hands. The intermediate gear 6 is actuated by a transmission gear 7 rotated by the winding stem 1 when it is in a hand-setting mode.

The winding mechanism according to the invention comprises a winding gear 8 mounted for rotation on the winding stem 1 and has ratchet teeth 8a on an upper surface thereof with peripheral teeth meshing with a ratchet gear 10 that is used for winding the winding spring in the watch. The ratchet gear 10 is constantly in mesh with the winding gear 8. The winding gear 8 is protected by a winding gear guard 9 secured on the barrel bridge 4 and serves to control the axial movement of the winding wheel or gear 8 as later described.

In order to wind the winding mechanism, the mechanism is provided with a clutch gear 11 mounted coaxially with the winding gear 8 and having teeth for meshing with the ratchet teeth 8a of the winding gear. The clutch gear 11 is mounted on a square or rectangular cross-section portion 1b of the winding stem 1 for rotation with the winding stem and to allow axial movement of the clutch gear relative the winding stem. The clutch gear 11 is biased by biasing spring 12 in a direction for meshing it with the clutch teeth of the winding gear. The spring 12 is disposed within the cylindrical or tubular portion 2a of the crown 2. This reduces the thickness of the watch. When the crown and winding stem are in a position shown, a winding or first position is established in which the winding mechanism can be wound for winding the watch. In order to set the hands of the watch, the crown 2 and winding stem 1 are pulled outwardly and the transmission gear 7 is meshed or engaged with the intermediate hand-setting gear 6 for setting the hands. A collar 1c lifts the clutch gear 11 from engagement with the winding gear 8 against the biasing force of the spring 12 so that rotation of the crown for setting the hands does not affect the winding mechanism.

When the winding stem is in the position illustrated in FIG. 1 the winding mechanism can be wound by rotating the winding stem into an angular position in which the clutch gear engages with the winding gear under the control of its biasing spring and the winding mechanism is accordingly wound. In the event that the winding crown is rotated in a reverse direction the clutch gear teeth of the winding gear 8 cause the clutch gear 11 to move away axially from the winding gear against the resiliency of the spring 11 to prevent damage to the gears and winding mechanism. During the movement away from the clutch gear a sound signal is effected.

Moreover, when the winding crown 2 and winding stem are moved to the second position thereof, for setting the hands of the clock, the collar 1c of the winding

stem engages a stepped portion 11a of the clutch wheel. The clutch wheel or gear is moved against the resiliency of the spring 12. The winding gear guard 9 prevents the winding gear 8 from moving with the winding stem in an axial direction whereby the winding gear 8 is constantly kept in engagement with the ratchet gear 10 during the hand-setting operation. After the setting of the hands has taken place, the crown 2 is returned to the position as shown in FIG. 1 and the clutch gear 11 is biased by the spring 12 so that it again meshes with the ratchet teeth 8a of the winding gear 8 whenever the gears are in angular phase for this engagement.

A second embodiment of the invention is illustrated in FIG. 2. In this embodiment a winding stem 1' has a rectangular or square cross-section 1'b and a crown not shown. It extends axially through a casing member, not shown, a barrel bridge 4' and a plate 5'. The winding stem 1' drives a hand-setting mechanism having a hand-setting or intermediate gear 6' which is driven by a transmission gear 7' mounted on the winding stem 1' when it is moved to a hand winding position upwardly.

A winding mechanism is provided in the present invention similarly to the first embodiment. A winding gear 8' is rotationally mounted on the winding stem and meshes continuously with a winding gear 10'. A clutch gear 11' is provided and in this instance is disengaged from the winding gear by a shoulder 1d' which engages a shoulder 11'a of the clutch gear when a hand-setting operation is effected. A guard plate 9' keeps the winding gear 8' meshing with the ratchet gear 10'. The clutch gear 11' is in this instance biased by a plate spring 12' which has a portion biasing the clutch gear and is anchored as shown to the watch.

A hand-setting gear 6' meshes with a transmission gear during a hand-setting operation as described before as to the first embodiment.

Thus provision is made in the present invention to eliminate the problems heretofore mentioned with respect to conventional watches. The crown may be rotated in opposite directions without any problem. Moreover, it is possible to lessen the thickness of the watch because the spring 12 is housed in the winding crown 2 or in a watch case as shown in FIG. 2. Shocks on the winding crown are absorbed by the winding gear 8 and the barrel bridge 4 by means of the flange 1c of the winding stem so that damage to the watch movement can be eliminated.

What I claim and desire to secure by Letters Patent is:

1. A winding mechanism comprising a winding stem mounted for rotation for winding a watch-winding mechanism in a winding first position and movable axially to a hand-setting second position for rotation for setting hand-setting mechanism, a winding crown mounting said winding stem for rotation and axial movement, a winding gear mounted for rotation about said winding stem and having peripheral teeth and ratchet teeth, a ratchet gear meshing with the peripheral teeth of said winding gear, a clutch gear mounted coaxially with said winding gear and axially slidable on said winding stem for rotation therewith, spring means housed in a space defined between said winding stem and said winding crown and constantly resiliently biasing the clutch gear axially on said winding stem in a direction for meshing with said ratchet teeth of the winding gear and allowing said clutch gear to be displaced

5 axially away from said winding gear when said crown is rotated in a direction opposite to a winding direction for winding said winding mechanism, and means on said winding stem to displace said clutch gear axially 10 away from said winding gear against a biasing force of said spring means when said winding stem is moved axially from said first winding position to said hand-setting second position.

2. A winding mechanism according to claim 1, including guard means for preventing said winding gear from moving axially with said stem, whereby said winding gear and said ratchet gear mesh at all times.

3. In a watch, a winding stem mounted for rotation for winding a watch-winding mechanism in a winding 15 first position and movable axially to a hand-setting second position for rotation for setting hand-setting mechanism, means mounting said winding stem for rotation and axial movement, said winding mechanism comprising a winding gear mounted for rotation about said 20 winding stem and having peripheral teeth and ratchet teeth, a ratchet gear meshing with the peripheral teeth of said winding gear, a clutch gear mounted coaxially with said winding gear axially slidable on said winding stem for rotation therewith; spring means constantly 25 resiliently biasing the clutch gear axially on said winding stem in a direction for meshing with said driving gear clutch teeth and allowing said clutch gear to be displaced axially away from said clutch gear if said clutch gear is rotated by said winding system in a direction opposite to a winding direction for winding said 30 winding mechanism, means on said winding stem to displace said clutch gear axially away from said winding gear against a biasing force of said spring means when said winding stem is moved axially to said second position 35 thereof, and said means on said stem comprising a portion having a diameter defining a shoulder for engaging said clutch gear.

4. In a watch, a winding stem mounted for rotation for winding a watch-winding mechanism in a winding 40 first position and movable axially to a hand-setting second position for rotation for setting hand-setting mechanism, means mounting said winding stem for rotation and axial movement, said winding mechanism comprising a winding gear mounted for rotation about said 45 winding stem and having peripheral teeth and ratchet teeth, a ratchet gear meshing with the peripheral teeth of said winding gear, a clutch gear mounted coaxially with said winding gear axially slidable on said winding stem for rotation therewith, spring means constantly 50 resiliently biasing the clutch gear axially on said winding stem in a direction for meshing with said driving gear clutch teeth and allowing said clutch gear to be displaced axially away from said clutch gear if said clutch gear is rotated by said winding system in a direction opposite to a winding direction for winding said 55 winding mechanism, means on said winding stem to displace said clutch gear axially away from said winding gear against a biasing force of said spring means when said winding stem is moved axially to said second position thereof, and said means on said stem comprising a collar on said stem disposed on said stem for engaging said clutch gear.

5. In a watch, a winding stem mounted for rotation for winding a watch-winding mechanism in a winding 60 first position and movable axially to a hand-setting second position for rotation for setting hand-setting mechanism; means mounting said winding stem for rotation

and axial movement, said winding mechanism comprising a winding gear mounted for rotation about said winding stem and having peripheral teeth and ratchet teeth, a ratchet gear meshing with the peripheral teeth of said winding gear, a clutch gear mounted coaxially with said winding gear axially slidale on said winding stem for rotation therewith, spring means constantly resiliently biasing the clutch gear axially on said winding stem in a direction for meshing with said driving gear clutch teeth and allowing said clutch gear to be 10

displaced axially away from said clutch gear if said clutch gear is rotated by said winding system in a direction opposite to a winding direction for winding said winding mechanism, means on said winding stem to displace said clutch gear axially away from said winding gear against a biasing force of said spring means when said winding stem is moved axially to said second position thereof, and said spring means comprising a spring housed in said crown.
